UNITED STATES PATENT OFFICE.

PATRICK J. CLIFFORD, OF FALLS, AND JOHN H. GIBBS AND HENRY P. LYNCH, OF SCRANTON, PENNSYLVANIA, ASSIGNORS, BY MESNE ASSIGNMENTS, TO TRAIN CONTROL CORPORATION OF AMERICA, A CORPORATION OF DELAWARE.

MEANS FOR CONTROLLING AUTOMATIC TRAIN-STOP MECHANISM FROM TRACK SIGNALING SYSTEMS.

Application filed February 19, 1921, Serial No. 446,417. Renewed December 10, 1927.

In application for Letters Patent of the United States filed by P. J. Clifford, March 24th, 1919, Serial No. 284,731, is disclosed an automatic train stop system which is 5 operated by air pressure supplied thereto through a valve which is operated by a contact device on the engine running over a ramp located alongside the track. Our present invention is designed to avoid the 10 use of the ramp and contact device and instead employ electrically operated means for controlling the actuation of the air supply valve, which means is capable of combination with and control by signal systems now in use, such as the Hall, so that a 15 train equipped with the Clifford automatic pneumatically operated train stop system will be controlled from the same electrical apparatus which controls the signals.

20 It will be understood, however, that while our invention is described hereinafter in connection with the Clifford automatic train stop system, its use is not limited to any particular train stop system, nor to any particular 25 signaling system like the Hall, and therefore the following description is to be regarded as illustrative of one but not the only embodiment of which our invention is capable.

30 The drawing in Figure 1 shows a diagram of the invention including a portion of the standard Hall signaling equipment in light full lines at the lower part of the diagram, our present invention in heavier lines, and 35 a portion of the automatic train stop mechanism on the engine of the Clifford type.

Figure 2 is a detail view of the electrically 40 operated air valve which supplies air pressure for actuating the automatic train stop mechanism.

Figs. 3 and 4 show details.

In the diagram we have shown a single track road but it will be understood that the invention may be used on a road of any 45 number of tracks or on any part thereof which is supplied with an automatic signaling system.

In this diagram the track is indicated divided into blocks, 1, 3, 5 and 7. The semaphores are indicated at S and the vehicle or 50 engine with which this description deals is indicated at E on block 1. The standard

signaling equipment is shown in part only, this being in full light lines, the parts omitted being unnecessary to a clear understanding of the present invention. This equipment includes the track battery TB, the semaphores, the "common wire", certain batteries, the 90° and 45° connections, and other parts, all of these for clearness of illustration being located at the bottom of the diagram or below the tracks, excepting the semaphores.

Parts now to be described are located on the engine—

The electric air valve on the engine which controls the supply of air to the automatic train stop mechanism is shown at EAV, and one object of the present invention is to open this valve to supply air to the automatic 70 train stop mechanism when the semaphore approached by the engine is set at "Caution", i. e., 45°, or at "Danger", i. e., horizontally.

This valve is controlled by a battery VB. It is held closed to cut off the air to the 75 automatic train stop mechanism so long as current from this battery is flowing through the circuit wires 2 and 4, but when the flow of this current ceases the valve EAV will open and supply air to the automatic train 80 stop mechanism, and, as a result, the train will be slowed down or stopped. The flow 85 of current through the valve circuit 2, 4, is controlled by governor contacts 6 which are opened or closed by governor G driven by an electric motor M. So long as this motor is in operation the contacts at 6 will be open, because the governor will draw down the contact bar 6' and the current through the 90 valve circuit 2, 4, and battery VB will be maintained, but when this motor M stops then the contacts at 6, 6', will be closed, establishing a circuit with battery VB of

lower resistance than the valve circuit 2, 4, with the result that current from battery VB 95 will flow through circuit 7, 8, and not through 2 and 4, and the valve EAV will open and admit air to the automatic train stop mechanism. Circuit 7, 8, includes governor controlled contacts 9, as will be described hereinafter.

The motor M is energized from battery MB when relay 10 closes circuit 11, 12, which includes battery MB, and it is de-energized

when relay 10' closes circuit 11', 12', which also includes battery MB. Relay 10 is so wound or its armature is positioned close enough to its magnet pole to be operated by a weak current derived from the track battery through the wheels W of the pony truck and through circuit wires 13, 14. This current is too weak to operate relay 10'. This latter relay is operated to close circuit 11', 12', and cut out the motor when current additional to that sufficient to operate the relay 10 is impressed on circuit 13, 14, which happens as presently will be described. The relay 10' is connected across circuit 13, 14, 15 by branch wires as shown. The circuit 11', 12', is of low resistance as compared with circuit 11, 12, so that when both of these circuits are closed by their relays, current from battery MB will take the path of least 20 resistance, i. e., through circuit 11', 12', and relay 10', and will not pass through the motor, which consequently will stop.

It will now be seen from the above description that when relay 10 alone is closed, 25 because of the weak current in circuit 13, 14, the motor M will be driven, contacts 6 will be open, and current from battery VB flowing through circuit 2, 4, will hold the valve EAV closed and prevent air pressure 30 going to the automatic train stop mechanism, and the diagram illustrates this condition. This condition will exist when the blocks ahead of the engine are "clear", the only current present in the circuit 13, 14, being 35 that derived from the track battery through the pony truck W.

All of the parts above described between 40 valve EAV and the pony truck are carried on the engine. We will now describe other parts constituting a part of our improvement, located along the track and shown in heavy lines in the diagram at the portion thereof which lies below the tracks.

Now in order to impress the additional 45 current on the line 13, 14, for operating relay 10', stopping motor, closing contacts 6, and thus taking all current from circuit 2, 4, of the valve EAV for opening said valve, we employ a battery which we have called a 50 brake battery and have indicated at BB. This battery is connected across the rails of the track by leads 15, 16, and this circuit includes contacts 17 controlled by a cross piece 17' operated by what may be termed 55 the brake relay and marked BR. This relay we cut into the wire which we have marked "90° control" this being part of the standard equipment of the Hall signal system.

When the block ahead of the train is clear, 60 current will be flowing in this wire, but when the block ahead is set at "Caution" or "Danger", then no current will be in this wire. These conditions are those existing in signaling systems as will be understood by 65 those skilled in the art.

In the former case, i. e., with the block ahead clear, the relay BR will be energized and contacts 17 will be open and no current will be impressed on circuit 13 and 14 through the rails and pony truck from the 70 brake battery BB, and hence only relay 10 will be closed, because only the weak current from track battery TB will pass through the circuit 13, 14. The air supply valve EAV will therefore remain closed and 75 there will be no application of the brakes.

Under the other condition mentioned, however, i. e., when the next or second block ahead is occupied and no current is flowing in "90° control" wire, the brake relay BR 80 will be de-energized, allowing contacts at 17 to close, thus impressing current from brake battery BB upon the circuit 13, 14, through the pony truck, whereupon both relays 10 and 10' will close their contacts and the motor M will cease its revolution, because of the current from battery MB taking the path of least resistance through 11', 12', and thus excluding the motor. Contacts at 85 6, 6', will therefore close and current taken from the air valve circuit, allowing this to open and the brakes to be set, by supplying air pressure to the automatic train stop mechanism on the engine.

Reverting to the governor controlled contacts 9, we have shown these in Fig. 1, and the governor of a diagrammatic form, sufficient to lead to a clear understanding of the general purpose of this mechanism, whereas, in Fig. 3 we have shown the refinement 100 of this mechanism in order to disclose the particular functions which it performs, and in connection with a thermostat control device hereinafter fully described. These contacts 9 are closed by a cross piece 9' connected with a speed governor SG driven from a wheel W of the engine running on the rail, and connected to the speed governor by a suitable flexible shafting 68. This governor is set to open the contacts at 9 when the 110 train is running below the prescribed slow speed, under the full control of the engineer, say, for instance, at 10 miles an hour. When running below this low speed, this governor by opening the contacts at 9 eliminates the 115 means above described for controlling the train stop mechanism, because with the circuit 7, 8 open, there can be no shunting of current from the air valve circuit 2, 4, and this valve will remain closed even though 120 motor M should stop in consequence of a block ahead being occupied. The train running at this slow speed can be quickly stopped by the engineer should the track remain obstructed.

If, however, the train is running at a higher speed than that considered to be safe, say, for instance, at any speed above 10 miles an hour, the speed governor SG will draw down the bar 9' and close contacts 9, 9, and 125 130

therefore the air valve circuit will be under the control of the automatic electrical apparatus above described, and the air valve EAV will open automatically when the next ² or second block ahead is occupied.

There may be a condition arise where the engineer, after having brought his train down to the low speed for quick control, becomes incapacitated or careless and could ¹⁰ not or would not obey a danger signal, and for taking care of this condition the mechanism shown in Fig. 3 is provided, which includes a thermostat T controlling certain contacts for shunting the circuit 2, 4 of ¹⁵ valve EAV should the train continue running for a prescribed time beyond a caution board without control by the engineer. Under this condition, the valve EAV would be opened and the train would be stopped, ²⁰ unless, of course, the track ahead cleared before the danger point had been reached.

The governor of Fig. 3 includes an insulated portion 20 and a conducting portion 21, roller contacts 9" bear on the insulating ²⁵ material 20 when the train is running at the prescribed low quick control speed and therefore all the control apparatus is cut out and the valve EAV will remain closed, despite any changes in the track signal ³⁰ circuits, and the brakes will not be applied unless the train continues a prescribed time with the danger board set against it, whereupon control will be exerted through the thermostat T. This thermostat has a coil ³⁵ 22 connected across the circuit 7, 8 and this coil is adapted to heat up the U-shaped wire 23 which is provided with contact 7'. This contact, when the U-shaped wire spreads, closes the circuit at contact 8' and provides ⁴⁰ a path, for the current, of low resistance as compared with that through the coil 22, this low resistance path being through the U-shaped wire of the thermostat and thus current from battery VB will be shunted from circuit 2, 4, and valve EAV will open and the train will be stopped before it reaches ⁴⁵ the danger board set against it. If the track clears before the train travels the prescribed distance beyond the caution board necessary ⁵⁰ to cause the thermostat to heat up, then the conditions of the track circuits will be changed and motor M by starting will open contacts at 6, 6', and valve EAV will remain closed for the continued movement of ⁵⁵ the train.

When the train speeds up, the bar 20, 21 will be drawn down by the governor and the conducting portion 21 will then be between the roller contacts and circuit 7 and 8 will ⁶⁰ be closed at this point ready to be fully established when contacts at 6, 6' close. The movement of the bar 20, 21 downwardly will break the thermostat connection at 24, and this will remain in this condition until the ⁶⁵ bar 20, 21 again rises. This is done by collar

25 on the bar 20, 21 operating against the yielding part 26 of the thermostat connection.

It will now be seen that if the engineer is running the train at the safe slow speed past ⁷⁰ a caution board, and having passed it becomes incapacitated while approaching the next board, set at danger, the following action will result:

The continuance of the overcharge current ⁷⁵ from battery BB impressed on circuit 13, 14 will maintain contacts 6, 6' closed and the coil of thermostat T will gradually heat up, because this is now in circuit with battery ⁸⁰ VB.

During the running of the train for the prescribed time at slow speed, the thermostat is heating up and the U-shaped wire is expanding or spreading, its contact will make circuit at 7', 8', with the result that circuit ⁸⁵ 7 and 8 will now offer sufficiently low resistance for short circuiting the EAV valve which will then open and the brakes will be set.

If any wire or electrical connection fails, ⁹⁰ the EAV valve will open and set the brakes. As one contributing factor to this result we have placed a relay or circuit breaker at 26' in the circuit 2, 4 of valve EAV, which receives current to keep it closed so long as ⁹⁵ current is passing through resistance 27 connecting across the contacts at 6, 6'. A high resistance circuit is thus established, including circuit wires 7, 8, battery VB, coil 26" of the circuit breaker 26', and resistance coil ¹⁰⁰ 27. This normally closed circuit is of high enough resistance to prevent shunting current entirely from circuit 2, 4 of valve EAV and consequently this valve will remain ¹⁰⁵ closed.

If, however, any of the circuit wires break or other parts fail between contacts 6, 6' and valve EAV, the circuit breaker coil 26' will be de-energized and open circuit 2, 4 of valve ¹¹⁰ EAV with the result that this valve will open and the brakes will be set.

A similar automatic setting action will result from the breaking of any connections between the contacts 6, 6', and the track battery, such as the circuit 13, 14, or the ¹¹⁵ branch connections to the relay 10', as will be hereinafter described.

Valve EAV.

The valve EAV includes a casing containing a slide valve having a port 28 controlling the flow of air pressure from the equalizing reservoir to the automatic brake system.

This valve is forced normally to the right to the closed position by a spring 29. ¹²⁵

It is moved to open position by a strong spring 34 upon de-energizing an electromagnet 30, the armature 31 of which has a stem 32 provided with a pawl 33 pivoted thereto and engaging a notch in the stem of ¹³⁰

the valve. The electro-magnet is energized by circuit 2, 4 and so long as this circuit is maintained the armature will be held towards the right and the valve will be closed.

- 5 As soon, however, as circuit 2, 4 is shunted, and the electro-magnet is de-energized, spring 34, stronger than spring 29, will pull the pawl towards the left and draw the valve into its open position. As soon as
- 10 this takes place, however, the pawl will be released from the valve rod by its incline 35 riding up on the pin 36 and the valve will immediately return to closed position under the action of its spring 29.
- 15 The valve is open only a short space of time, as this will admit sufficient air pressure to the system to apply the brakes.

We have provided means whereby after the valve has operated and has returned to its closed position under the action of its spring, the electro-magnet will be energized again for causing the pawl to re-engage the valve stem ready for another application of the brakes.

- 20 25 This means is intended to perform its function whether the brakes are set at high speed or at low speed. It consists of a thermostat T' in the shunting circuit 7, 8 of the valve battery VB.

- 30 When the opening of the valve EAV and its return to closed or disconnected position takes place by current passing through this circuit 7 and 8 with the train running at high speed, and with the circuit completed 35 through the governor at 21, this thermostat will heat up, break the low resistance circuit through this thermostat T' while maintaining the high resistance circuit here and permit current from battery VB to pass through the magnet of the valve EAV and cause the pawl to move to the right and couple up again with the valve stem, ready for another operation and application of the brakes. The thermostat T' does not open the circuit 40 of relay magnet 26', but maintains this circuit through the fine wire coil which forms a part of this thermostat and this keeps the relay 26' energized. At the same time the coil of this thermostat will, when heated, break the low resistance and thus prevent shorting circuit 2, 4.

- 45 The same thing takes place when running at low speed after the brakes have been set by closing of the circuit 7, 8 at the thermostat T. When this happens, valve circuit 2, 4 is shunted and valve EAV immediately opens and then closes and is now in disconnected condition. Current is now passing through circuit 7, 8, including thermostats 50 T and T'. The latter will heat up, break low resistance part of circuit 7, 8 and restore circuit 2, 4 to activity, and cause the valve EAV to be connected up for another application of the brakes. On cooling, thermostat T' will close the circuit 7, 8 and

thermostat T will open its branch connection.

We provide a safety device to secure an application of the brakes, in case the relay 10' or its connections fail.

It will be obvious that, as regards the relay 10, if this fails, or its circuit is broken, including the track battery branch 13, 14, this relay will open, the motor M will stop, or if a magnet is used in place of the motor, 75 this will be de-energized and contacts 6, 6' will close to secure an application of the brakes.

The safety device for the relay 10' and its connections includes an electro-magnet 37 80 in the branch circuit across the circuit 13, 14, and an armature 38 acting as a circuit breaker in the wire 13 of circuit 13 and 14. The magnet 37 will be energized by current of about the same strength as that which energized the relay magnet 10, and so long as the branch circuit which includes magnet 37 and magnet of relay 10' remains intact, the circuit 13, 14 will be maintained and relay 10 will be energized. If, however, the magnet of relay 10' or the branch circuit in which it is located fails, then the circuit 13, 14 will be opened at 37 and relay 10 will release its armature and motor M will stop, and an application of the brakes will take 95 place.

It will be observed in this connection that our brake controlling means operates on the closed circuit system. For instance, the valve EAV remains closed so long as circuit 2, 4 is supplied with current. If this circuit breaks, or if the circuit 7, 8, breaks, then the valve EAV will be opened, because the breaking of circuit 7, 8, will result in breaking of the valve circuit 2, 4, on account of 105 the opening of the circuit breaker with which the latter circuit is provided, as above described.

Also if the closed track battery circuit 13, 14 breaks, contacts 6, 6' will close as a consequence of the stopping of the motor, and a brake application will result, or if the relay 10' or the branch circuit in which it is located fail, the circuit 13, 14 will be opened and thus a brake application will take place 110 by reason of the stoppage of the motor M. We trace the circuits in the roadside signaling system and relay BR under different conditions as follows:

Case 1. Train on block #5 only.

Both 4 ohm relays on track #5 deenergized. Circuit through relay BR remains open at the contact *a*.

Case 2. Train on block #3 only.

Both 4 ohm relays on track #3 deenergized.

Circuit: through relay BR, through contact *a*, through contact *c*, common wire *d*, 130

contact *e*, back to relay BR, which means that relay BR is short-circuited on itself, i. e. deenergized.

Case 3. No train on any block.

5 All 4 ohm relays are energized.

Circuit: relay BR, contact *e*, conductor *f*, contact *g*, 50 ohm relay, conductor *h* and contact *k* which is broken, relay BR deener-
10 gized.

Case 4. Train on block #1.

4 ohm relay on track #1 are deenergized.

Circuit: relay BR, contact *e*, conductor *f*,
15 contact *g*, 50 ohm relay, conductor *h*, contact *k*, to common wire *d*, conductor *m*, minus of battery #5-7, plus of battery #5-7, contact *n*, 45° connection of block #5, contact *o*, 800 ohm relay, conductor *b*, contact *a*, and
20 back to relay BR.

It will be understood that the apparatus above described is illustrative of our invention and is not to be considered in a restrictive sense, and changes can be made
25 without departing from the principles involved.

It will be understood that while we have shown the relay means conventionally, they are of such sensitive character as to meet the
30 conditions under which they are intended to work.

We claim:—

1. In train stop apparatus a device for controlling the operation of the brakes, a
35 signaling system including a track battery, a means supplied with current from said track battery when the line is clear for maintaining said device against operation, a brake battery in the signal system for supplying additional current when a caution or danger
40 signal is set against the train, said additional current controlling said means to cause the operation of the said device to set the brakes, substantially as described.

45 2. In train stop apparatus, a device for controlling the setting of the brakes, a track-way system including a track battery, a relay arranged in one of the trackway wires, a brake battery controlled by said relay to supply additional current when the relay closes consequent upon the absence of current in the said wire, and means controlled by the track battery current and by the additional current from the brake battery for
50 controlling the operation of the said device.

3. In train stop mechanism the combination of a device on the vehicle to control the setting of the brakes, a trackway system including a track battery, a pair of relays on the vehicle and in circuit with the track battery, one adapted to be operated by current in the track battery circuit, and the other by additional current impressed on the track battery circuit, a brake battery for impressing the additional current on the

track battery circuit, a relay in one of the signaling wires of the trackway system for controlling the brake battery, means controlled by the said pair of relays for maintaining the said device inoperative
70 while the weak current of the track battery is flowing and for operating the said device when the additional current is flowing, substantially as described.

4. In combination, automatic train stop
75 mechanism, a valve for supplying air thereto for setting the brakes, an electric trackway system, electrical apparatus on the vehicle controlled by the conditions in the trackway system for maintaining said valve
80 closed when the track is clear and for opening said valve for the inlet of air pressure to the brake system when a caution or danger signal is set, a speed governed device controlling a contact of said electrical apparatus to prevent operation of the valve when the train is running at a prescribed reduced speed, and means for restoring the function of the said electrical apparatus to operate the said valve for setting the brakes should the train continue at the reduced speed for a prescribed interval prior to a change in the signals, said electrical apparatus on the vehicle including relay means in a conductor receiving current from the traction rail system due to the drop in potential between the points of contact of said conductor with said rail system, substantially as described.
85

5. In combination in train stop apparatus, an electrically operated air valve, a
90 battery and circuit connections for controlling said air valve, a shunting circuit for said battery, contacts controlling said shunting circuit, an electric device controlling said contacts, a battery and circuit connections for controlling said device, a relay for closing said circuit, said relay being in the track battery circuit of the signaling system, a second relay in said system operable when additional current is impressed
95 on the track battery circuit, a circuit for shunting the electric device battery from the electric device controlled by said second relay, a brake battery for impressing the additional current on the track battery circuit, and a relay in the signal system for controlling the brake battery, substantially as described.
100

6. In combination, automatic train stop
105 mechanism, a valve for supplying air thereto for setting the brakes, an electric trackway system, electrical apparatus on the vehicle controlled by the conditions in the trackway system for maintaining said valve closed when the track is clear and for opening said valve for the inlet of air pressure to the brake system when a caution or danger signal is set against the train, a speed governor controlling contacts for eliminating the function of the said elec-
110
115
120
125
130

- trical apparatus to prevent operation of the valve when the train is running at a prescribed reduced speed, and means for restoring the function of the said electrical apparatus to operate the said valve for setting the brakes should the train continue at the reduced speed for a prescribed time prior to a change in the signals, substantially as described.
7. In connection with the features of claim 6, the restoring means therein mentioned consisting of a thermostat having a resistance coil, which, when heated by the continued flow of the current therethrough while the train is running at reduced speed in response to a caution or danger signal, will close the circuit previously opened by said governor to effect the opening of the valve and the setting of the brakes.
8. In combination with an automatic train stop system, including a valve for admitting air pressure into the system for applying the brakes, a signal system along the tracks for indicating when the track is clear or obstructed, said system including a "90° control" wire and a track battery, means controlled by the track battery when current is in the "90° control" wire consequent upon a clear track for maintaining the air valve closed, and means rendered effective when no current is present in said control wire consequent upon the track being obstructed, for furnishing current additional to that furnished by the track battery for causing said first mentioned means to open the air valve, substantially as described.
9. In combination with an automatic air pressure operated train brake system, a valve for supplying air pressure thereto, a battery, circuit connections, and means controlled thereby for maintaining the valve shut so long as said circuit is supplied with current, a signaling system to indicate to the engineer caution, danger or a clear track, and means actuated by and in response to changes in the conditions thereof for shunting said circuit for the opening of the air pressure valve when a caution or danger board is set against the train, said signaling system connecting up with said last mentioned means through the ordinary track rails, so that said means is subject to operation at all times, substantially as described.
10. In combination with an automatic train brake system, an air valve for supplying air pressure thereto for setting the brakes, a battery, and electro-magnetic means in a normally closed circuit for allowing the air valve to remain closed as long as the said circuit is closed, a circuit including said battery to shunt current from the normally closed circuit first mentioned, means for closing said shunting circuit, a circuit breaker in the normally closed circuit energized by current in the shunting circuit to maintain said closed circuit and to open the normally closed circuit upon failure of the shunting circuit to thereby cause the opening of the valve and the setting of the brakes.
11. In combination, brake setting mechanism, an air valve controlling the admission of air thereto for setting the brakes, a signaling system for setting signals along the track against the engineer, said signaling system including a track battery, a branch circuit on the engine connected with the track battery circuit through the engine and rails, a relay in said branch circuit, a battery and circuit controlled by the said relay, means in said relay circuit for controlling the valve, a second relay for shunting the relay circuit, a circuit breaker in the branch circuit of the first relay, the magnet of which is in the branch of the second relay, whereby if said second relay fails, the first relay will open and the brakes will be set by the opening of the air valve, substantially as described.
12. In train stop systems, an air valve for controlling air pressure to the brake mechanism for setting the brakes, a signaling system for setting signals against the engineer, including a track battery, a relay on the train in a branch of the track battery, means energized by the relay circuit, means controlled thereby for maintaining the air valve closed so long as said relay circuit is maintained, a brake battery alongside the track for impressing additional current on the track battery circuit and its branch on the train, a relay across the branch circuit energized by the additional current impressed on said branch circuit for shunting the battery of the relay circuit first mentioned, and a circuit breaker for the first relay controlled by the circuit of the second relay whereby if either relay fails the air valve will open to apply the brakes, substantially as described.
13. In combination with automatic train stop apparatus, a valve for admitting air pressure for operating said apparatus for setting the brakes, a battery, electro-magnetic means in circuit with the battery, said valve being in closed position when the said battery circuit is closed, a second circuit including said battery which when closed shunts the current from the first mentioned circuit to thereby cause the opening of the valve and the setting of the brakes, and thermostatic means in the second circuit for breaking the same to thereby render active the first circuit for placing the valve in condition for another application of the brakes, all the above mentioned parts being on the train.
14. In combination with automatic train stop apparatus, a valve for admitting air pressure for operating said apparatus for setting the brakes, a battery, electro-magnetic

- means in circuit with the battery, said valve being in closed position when the said battery circuit is closed, a second circuit including said battery which when closed 5 shunts the current from the first mentioned circuit to thereby cause the opening of the valve and the setting of the brakes, and thermostatic means in the second circuit for breaking the same to thereby render active 10 the first circuit for placing the valve in condition for another application of the brakes, all the above mentioned parts being on the train, a signaling system for setting signals along the track against the engineer, contacts 15 normally open in said shunting circuit, and means on the train for closing said contacts, said means being controlled from the signaling system according to changes therein, due to the positions of the signal boards, 20 substantially as described.
15. In combination with automatic train stop mechanism, an air valve for admitting air pressure thereto, comprising a casing, a valve member, a spring for moving the valve member to closed position, a stronger spring for moving the valve member to open position, a detachable connection between the strong spring and the valve member, an electro-magnet and armature for coupling 25 said strong spring to the valve and for opposing the force of the strong spring, a battery in circuit with the electro-magnet and means for controlling said circuit, said strong spring when the magnet is de-energized opening the valve, substantially as described.
16. In combination with automatic train stop mechanism, an air valve for admitting air pressure thereto, comprising a casing, a valve member, a spring for moving the valve member to closed position, a stronger spring for moving the valve member to open position, a detachable connection between the strong spring and the valve member, an electro-magnet and armature for coupling 30 said strong spring to the valve and for opposing the force of the strong spring, a battery in circuit with the electro-magnet and means for controlling said circuit, said strong spring when the magnet is de-energized opening the valve, substantially as described.
- 40 17. In combination with automatic train stop mechanism, an air valve, an electro-magnet and armature, a rod connected with the armature, a pawl on the rod to couple with the valve stem, a spring for moving the valve to closed position when the pawl is uncoupled, a strong spring connected to the rod for moving the rod and the coupled valve to open position when the electro-magnet is de-energized, and means for uncoupling the 45 pawl from the valve when the latter reaches its open position, so that the valve can return to closed position, the said electro-magnet when again energized moving the pawl carrying rod to engage with the valve and set the strong spring for another opening movement of the valve, substantially as described.
- 50 18. In combination with automatic train stop mechanism, an air valve for admitting air pressure thereto for setting the brakes, means for operating said valve to open position, an electro-magnet which when energized sets said operating means ready to act and couples the same with the air valve detachably, and when de-energized permits 55 said operating mechanism to open the valve, means for uncoupling the air valve from its operating means when it reaches its open position, said valve when uncoupled resuming its closed position, substantially as described.
- 55 19. In train stop apparatus a device for controlling the operation of the brakes, a trackway system including a track battery, means supplied with current from said track 60 battery when the line is clear for maintaining said device against operation, a brake battery in the trackway system for supplying additional current when a caution or danger signal is set against the train, said 65 additional current controlling said means to cause the operation of the said device to set the brakes, substantially as described.
- 65 20. In combination, means on the vehicle for automatically applying the brakes, electric controlling means in part on the vehicle and in part on the roadway for automatically operating the said brake applying means for setting the brakes when the train runs into a caution or danger block at high 70 speed, and to defer said brake setting when the train is running at a reduced speed until after a prescribed interval has elapsed, said vehicle carried means and said roadway means being in conductive circuit through 75 the track-way rails and parts on the vehicle constantly in contact therewith, substantially as described.
- 75 21. In combination, means on the vehicle for automatically applying the brakes, electric controlling means in part on the vehicle and in part on the roadway for automatically operating the said brake applying means for setting the brakes when the train runs into a caution or danger block at high 80 speed, and to defer said brake setting when the train is running at a reduced speed until after a prescribed interval has elapsed, said controlling means acting to prevent a brake application should the conditions in the 85 block change to clear before the said prescribed interval elapses, said vehicle carried means and said roadway means being in conductive circuit through the track-way rails and parts on the vehicle in constant contact 90

therewith, substantially as described.

22. In combination automatic brake application means on the vehicle, controlling means therefor including a governor and a timing device on the vehicle and trackway devices, said brake application means being operated to set the brakes at the prescribed time when the train is running at high speed and said brake setting being deferred when 10 the train is running at a reduced speed, said track-way devices and timing device being in a conductive circuit through the track-way rails and parts on the vehicle in constant contact therewith, substantially as described.
- 15 23. Automatic train stop mechanism including means on the vehicle for automatically applying the brakes, an electrical track-

way system in conductive circuit with the means on the vehicle, through the track-way rails and parts on the vehicle in constant 20 contact therewith, the vehicle carried means being operable to apply the brakes automatically at different times according to the speed of the train, i. e. at or near the time of entering the block at high speed and 25 after a prescribed interval of time has elapsed at a reduced speed, substantially as described.

In testimony whereof we affix our signatures.

PATRICK J. CLIFFORD.
